UNITED STATES PATENT OFFICE.

JAMES P. BECKER, OF MIAMI, FLORIDA, ASSIGNOR TO BECKER HARDWARE MANUFACTURING CO., OF MIAMI, FLORIDA, A CORPORATION OF FLORIDA.

CLOSURE OPERATOR.

Application filed June 14, 1927. Serial No. 198,716.

My invention relates to closure operators of the type utilized for securing casement or swinging window sashes in different angular adjustments with respect to their associated window frames.

My improved closure operator is particularly designed for use in window structures which embody a permanent window screen disposed inwardly of the swinging window sash. In such structures it is necessary that the casement window operating device extend through an opening in the screen frame and that its design be such as to exclude the passage of insects to the interior of a building by way of said opening when the window is either open or closed. All of the foregoing necessities inherent to the structural conditions enumerated are effectively met by my present invention and in addition many of the inventive concepts embodied therein are capable of use independently of the surrounding structural conditions I have particularly specified.

The advantages of my invention over known structures of this type, both from the standpoint of economic manufacture and installation and the standpoint of efficiency in use, will be apparent from the following detail description taken in connection with the accompanying drawings wherein like characters of reference denote corresponding parts in the several views, and in which:

Figure 1 is a fragmentary perspective view of a portion of a casement window showing my improved operating means applied thereto and in a position locking the window sash closed;

Figure 2, a view similar to Figure 1 showing the position of the parts of my improved operating mechanism securing the window sash in a partially open position;

Figure 3, a horizontal section through the parts of my improved operator showing the window sash locked in closed position and also showing, dotted lines, the operator bar in its initially engaged position with the sash locking element;

Figure 4, a detail front elevation of the sash and sill carried locking elements of my mechanism in the position they assume when the sash is locked closed;

Figure 5, a view similar to Figure 4 showing the position of the parts when the sash is released and free to be swung outward;

Figure 6, a front elevation of a portion 55 of the screen element; and

Figure 7, a perspective showing in detail the sill carried holding plate.

In the drawings A indicates generally a window frame which includes a sill 10. 60 Hinged to the frame A for outward swinging movement is a window sash 11. A screen 12 is mounted in the frame A as shown.

My improved device for operating the sash 11 and securing the same in different angular adjustments with respect to the frame A is shown as comprising an operator arm or bar 13 which is provided adjacent one end with a perforation 14 whereby it may be pivotally coupled to the sash 70 11 in a manner that will presently appear. The end of the bar 13 remote from the perforation 14 is provided with a suitable formation whereby it may be suspended from a convenient support when not in use; in the 75 present instance I show such formation as a hook 15. Along the length of the bar 13 I provide other perforations 16, the purpose of which latter will presently become apparent.

Mounted on the sash 11 is an angle member B one flange 17 of which is positioned against the sash while the other flange 18 thereof is disposed substantially at right angles to said sash and is provided with a laterally opening notch 19. Pivotally secured to and seated against the flange 17 of the member A is a flange 20 of another angle member C, while the flange 21 of the latter member is positioned beneath the flange 18 of the member A. Mounted on the flange 21 is a coupling pin 22 of such length that when the member C is in the position shown in Figures 2 and 5, the free end of said pin will seat in the notch 19. When the member is pivoted to the position shown in Figures 1, 3 and 4, it will be apparent that the coupling pin 22 will be so disposed that the operator bar 13 can be readily engaged on and disengaged from said pin through 100 the instrumentality of the perforation 14. Furthermore, it will be obvious that after

the bar 13 has been engaged on pin 22, as shown by dotted lines in Figure 3, an axial twist or rotation of the bar will move the member C from the position shown in Figures 3 and 4 to the position shown in Figures 2 and 5, when the flange 18 of the member B will secure said bar against disengagement from the pin. It will also be noted that the flange 21 of the member C 10 has a lateral extension 23 which, when the sash is closed and the member is in the position shown in Figures 1 and 4, engages behind a plate 24 secured to the sill 10 and thus the structure heretofore described 15 serves not only to provide a detachable pivotal coupling between the operator bar and sash, but in addition also provides a lock for securing the sash 11 closed and which is responsive to the operation of the parts 20 essential to effect engagement and disengagement of the operator bar on and from the pin 22.

The operator bar 13 when operatively coupled to the sash 11, extends through an 25 opening 25 in the frame of screen 12. At the base of this opening I secure to the sill 10 a plate 26 from which rises a holding pin 27 adapted to be selectively engaged in the 30 perforations 16 of the operator bar to secure the sash 12 in different angular adjustments with respect to the frame A. Also rising from the plate 26 is a guide pin 28 which serves as a bearing and guide for one edge of the bar 13 during operation of the 35 latter.

It will be observed that the opening 25 is considerably larger than the cross sectional area of the bar 13 in order that the latter may be freely manipulated in coupling and uncoupling the same with and from the pins 22 and 27 and for this reason it is necessary that means be provided to both secure the bar against accidental disengagement from the pin 27 and to also 40 completely close the opening 25 against the passage of insects therethrough irrespective of whether the bar 13 is entirely removed from said opening or is operatively associated with the device. To this end I secure 45 to the frame of the screen 12 a plate 29 having an opening 30 therein which registers with the opening 25. Slidably mounted on the inner face of this plate is a shutter 31 having an operating handle 32 which projects through and moves in an elongated slot 33 formed in the plate 29. The end of the shutter 31 adjacent the openings 25 and 30 is provided with a notch 34 positioned to snugly receive the bar 13 when closing 50 movement is imparted to the shutter. The notch 34 is of course of such depth to allow the shutter to partake of sufficient movement to close all portions of the openings 25 and 30 not occupied by the bar 13. It will be 55 noted that the portion of the shutter which,

in the closed position of the latter, overlies the bar 13, serves to secure said bar against disengagement from the pin 27. When the bar 13 is removed from the openings 25 and 30 the shutter 31 is capable of sufficient 60 movement to completely close said openings.

From the foregoing description considered in connection with the accompanying drawings, it is believed that the construction, operation and advantages of my invention will be clearly understood. I desire it to be understood, however, that I have simply illustrated and described my invention in the best form known to me at present, and that the same is capable of being expressed in many other forms and by an exceedingly wide range of mechanical equivalents without in any way departing from the scope of my invention as set forth in the appended claims.

I claim:

1. In a swinging closure operator, a coupling element adapted to be secured to a closure, said element having two positions in one of which an operator bar may be either interlocked therewith or disengaged therefrom, and means operable when said element is in the other of said two positions to prevent disengagement of an interlocked operator bar therefrom.

2. In a swinging closure operator, a coupling element adapted to be secured to a closure and including a coupling pin, said element having two positions in one of which a perforated operator bar may be either engaged on or disengaged from said coupling pin and means operable when said element is in the other of said two positions to prevent an operator bar engaged on the coupling pin from being disengaged therefrom.

3. In a swinging closure operator, a pivoted coupling element adapted to be secured to a closure, said element being movable to either of two positions in one of which an operator bar may be either interlocked therewith or disengaged therefrom, and means operable when said element is in the other of said two positions to prevent disengagement of an interlocked operator bar therefrom.

4. In a swinging closure operator, a pivoted coupling element adapted to be secured to a closure and including a coupling pin, said element being movable to either of two positions in one of which a perforated operator bar may be either engaged on or disengaged from said coupling pin, and means operable when said element is in the other of said two positions to prevent an operator bar engaged on the coupling pin from being disengaged therefrom.

5. In a swinging closure operator, a coupling element adapted to be secured to a closure, said element having two positions in

- one of which an operator bar may be either interlocked therewith or disengaged therefrom, means operable when said element is in the other of said two positions to prevent disengagement of an interlocked operator bar therefrom, and means embodied in the coupling element adapted, when said element is in the first named position, to cooperate with a fixed part to lock an associated closure against opening movement. 5
6. In a swinging closure operator, a coupling element adapted to be secured to a closure, said element having two positions in one of which an operator bar may be either interlocked therewith or disengaged therefrom, and a member adapted to be secured to a closure above said coupling element, said member securing an operator bar interlocked with the coupling element against 10 disengagement from said element when the latter is in the other of said two positions. 15
7. In a swinging closure operator, a coupling element adapted to be secured to a closure and including a coupling pin, said element having two positions in one of which a perforated operator bar may be either engaged on or disengaged from said coupling pin, and a plate adapted to be secured to a closure above the coupling element, said 20 plate having a notch receiving the coupling pin in the other of said two positions of the coupling element, to thereby prevent an operator bar interlocked with said pin from being disengaged therefrom. 25
8. In a swinging closure operator, an angle member having one flange provided with a notch and its other flange adapted to be secured against a closure, and a coupling pin pivotally mounted on the second named flange of said angle member for movement to either of two positions, in one of which a perforated operator bar may be engaged on or disengaged from the pin and in the other of which positions said pin seats in the notch of the first named flange of the angle member whereby said flange prevents an operator bar interlocked with said pin from being disengaged therefrom. 35
9. In a swinging closure operator, an angle member having one flange provided with a notch and its other flange adapted to be secured against a closure, a second angle member having one flange pivoted against the second named flange of the first angle member, whereby the second angle member may be moved to either of two positions, and a coupling pin carried by the other flange of the second named angle member adapted in one of the said positions of the second angle 50 member to permit a perforated operator bar to be engaged thereon and disengaged therefrom and in the other of said positions to seat in the notch of the first angle member whereby an operator bar interlocked with said coupling pin will be held against disengagement therefrom by the notched flange of the first angle member. 55
10. In a swinging closure operator, an angle member having one flange provided with a notch and its other flange adapted to be secured against a closure, a second angle member having one flange pivoted against the second named flange of the first angle member, whereby the second angle member may be moved to either of two positions, a coupling pin carried by the other flange of the second named angle member adapted in one of the said positions of the second angle member to permit a perforated operator bar to be engaged thereon and disengaged therefrom and in the other of said positions to seat in the notch of the first angle member whereby an operator bar interlocked with said coupling pin will be held against disengagement therefrom by the notched flange of the first angle member, and an extension on the coupling pin carrying flange of the second angle member adapted, when said member is in one of said two positions, to cooperate with a fixed part to lock an associated closure against opening movement. 60
11. In an operator for swinging closures, an arm adapted to be pivotally connected at one end to a closure, a fixed part having an opening of greater area than the cross sectional area of the arm and through which said arm operates, means for securing said arm in different positions to maintain an associated closure in different angular adjustments, and a shutter for closing that portion of said opening which is in excess of the cross sectional area of the arm. 65
12. In an operator for swinging closures, an arm adapted to be pivotally connected at one end to a closure, a fixed part having an opening of greater area than the cross sectional area of the arm and through which said arm operates, a fixed pin engageable selectively in perforations of the arm to maintain an associated closure in different angular adjustments, and a shutter for closing that portion of said opening which is in excess of the cross sectional area of the arm, said shutter extending over said arm when closed to thereby secure the arm against disengagement from said pin. 70
13. In an operator for swinging closures, an arm adapted to be pivotally and detachably connected at one end to a closure, a fixed part having an opening through which said arm operates, and a shutter operable, when said arm is detached from a closure and removed from said opening, to close the opening. 75
14. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 80
15. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 85
16. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 90
17. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 95
18. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 100
19. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 105
20. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 110
21. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 115
22. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 120
23. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 125
24. In an operator for swinging closures, an arm adapted to be pivotally connected at one end to a closure, a fixed pin engageable selectively in perforations of the arm to maintain an associated closure in different angular adjustments, and a member detachable from the fixed pin to thereby permit the closure to be opened. 130

ably engageable over said arm to thereby secure the arm against disengagement from said pin.

15. In a swinging closure, a coupling element adapted to be secured to a closure, and an operator bar adapted to be interlocked with and disengaged from said element when said bar is in one position with respect

to an associated closure, and means embodied in the element securing an interlocked bar against this engagement therefrom when said bar is in another position with respect to such associated closure.

In testimony whereof I hereunto affix my signature.

JAMES P. BECKER.

CERTIFICATE OF CORRECTION.

Patent No. 1,668,259.

Granted May 1, 1928, to

JAMES P. BECKER.

It is hereby certified that error appears in the printed specification of the above numbered patent requiring correction as follows: Page 4, line 11, claim 15, for the words "this engagement" read "disengagement"; and that the said Letters Patent should be read with this correction therein that the same may conform to the record of the case in the Patent Office.

Signed and sealed this 29th day of May, A. D. 1928.

(Seal)

M. J. Moore,
Acting Commissioner of Patents.
